UNITED STATES PATENT OFFICE.

WILLIAM C. LYON AND ALPHEUS McCULLEN, OF DURHAM, NORTH CAROLINA.

DISPLAY RACK.

Application filed April 10, 1924. Serial No. 705,528.

To all whom it may concern:

Be it known that we, WILLIAM C. LYON and ALPHEUS McCULLEN, citizens of the United States of America, residing at Durham, in the county of Durham and State of North Carolina, have invented certain new and useful Improvements in Display Racks, of which the following is a specification.

This invention relates to new and useful improvements in display racks adapted especially for the display of axes, ax handles and heads, and other similar articles.

An important object of the invention is to improve and simplify the construction of exhibiting racks so as to be comparatively inexpensive to manufacture, take up a minimum amount of floor space while having a large storage capacity, capable of being easily moved from place to place, and at the same time holding the axes in such a manner as to effectively display the same.

A further object of the invention is to provide a rack of the above mentioned type which may be easily and completely disassembled for permitting the same to be transported in compact form.

Other objects and advantages of the invention will be apparent during the course of the following description.

In the accompanying drawings forming a part of this specification and in which like numerals are employed to designate like parts throughout the same,

Figure 1 is a perspective view of the display rack embodying this invention,

Figure 2 is a side elevational view of the display rack illustrated in Fig. 1,

Figure 3 is an end elevational view of the rack illustrated in Figs. 1 and 2,

Figure 4 is a fragmentary view, partly in section and partly in top plan view taken upon lines IV-IV of Fig. 2,

Figure 5 is a fragmentary view, partly in section and partly in plan and taken upon line V-V of Fig. 3, and

Figure 6 is a fragmentary perspective view illustrating the manner of forming the lower portion of the leg of the frames employed for forming the rack illustrated in the aforementioned figures.

In the drawings, wherein for the purpose of illustration is shown a preferred embodiment of this invention, the numeral 5 illustrates a base which may be formed of wood or other suitable material and may be of either rectangular or square formation. Suit-

ably secured to the under face of the base 5 are the casters 6 which will permit the easy and rapid moving of the rack over the floor when so desired.

The rack consists of the similarly formed side frames 7 which are preferably manufactured from angle irons and are shaped to provide the perpendicularly extending leg portions 8 which are connected at their upper ends to the converging portions 9 that are joined by the arcuate top portion 10. As has been previously stated, these frames 7 are of identical formation and are intended to be positioned in parallelism with each other throughout their entire length.

In Fig. 6, one leg portion of one of the frames is illustrated as having the side 11 made into an extending lug 12 which is provided with an aperture 13. This extending portion 12 is intended to be bent into its dotted line position for permitting the same to be secured to the top face of the base 5 by the leg bolt 14. It will be seen that this construction permits the frames 7 to be suitably secured to the base 5. In Figs. 1, 3 and 5, there are shown transversely extending braces 15 which are secured to the leg portions 8 of the frames 7 by means of the stove bolts 16 which pass through suitable openings formed in the opposite ends of the transverse braces 15 and the said legs 8. It will be noted that these transverse braces 15 are positioned substantially midway of the distance between the lugs 12 and the point of connection between the leg portions 8 and the converging portions 9. Arranged on the same plane as the transverse braces 15 are the longitudinally extending lower braces 17 which are secured to the leg portions in a manner to be described at a later point. The frames 7 are further provided with upper longitudinally extending braces 18 which are connected to the converging portions 9 at a point spaced a suitable distance above the lower ends of these portions. By this construction, it will be seen that the transversely extending braces 8 act as means for retaining the side frames 7 in proper spaced relation to each other while the longitudinally extending braces 17 and 18 aid in strengthening the said frame portions 7.

As illustrated in Figs. 1 to 4 inclusive, the arcuate top portions 10 of the frames 7 are connected by the transversely extending pipe sections 19 which are secured to the said frames by means of the relative long tie

bolts 20 which extend through the bores of the said pipe sections 19. It will be seen that the upper portions of the frames 7 are in this manner suitably braced for retaining 5 the same in fixed spaced relation in respect to each other.

It will be seen, by inspecting Figs. 1 to 3 inclusive and 5 that the longitudinally extending braces 17 are secured to the side 10 frames 7 by means of the stove bolts 21 which pass through short sections of pipe 22. It is to be understood that these stove bolts 21 and pipe sections 22 are employed for the combined purpose of connecting the brace elements 15 17 to the frames 7 and for forming pegs for supporting ax heads such as those illustrated in Figs. 2 and 3 and referred to by the character H. It will also be seen, by inspecting Figs. 2 and 3, that the longitudinally extending upper braces 18 are connected to the converging portions 9 by the stove bolts 23 which pass through the bores of pipe sections 24. It is to be understood that these bolts and pipe sections 23 and 24 respectively 25 will form pegs for supporting ax heads H.

It will now be seen, by inspecting Figs. 1 to 5 inclusive that the braces 15, 17 and 18 and the side frames 7 are provided with a 20 multiplicity of ax head supporting pegs which are formed by the bolts 25 and pipe sections 26. These pegs may be arranged as desired and may extend laterally outwardly of the side frames, as indicated at —a— or 25 both laterally inwardly and outwardly of the side frames as indicated at —b— in Fig. 3.

In Figs. 2 and 3 the bars or pipe sections 19 are illustrated as being utilized for supporting and suitably displaying assembled axes with their handles depending from the said pipes 19. These figures also illustrate ax handles 27 which may be placed upon the top surface of the base 5 and stacked thereupon in positions to extend longitudinally of the rack and arranged between the side frames 7.

It is now believed that the manner of assembling this rack will be understood by 50 those skilled in the art and they will be able

to readily see that the entire device may be disassembled or knocked down for permitting the same to be shipped in a very compact form. It will also be seen that a great number of ax heads may be very artistically displayed and a desired number of assembled axes may also be displayed and provided in readiness for immediate sale. 55

It is to be understood that the form of this invention herewith shown and described 60 is to be taken as a preferred example of the same, and that various changes in the shape, size, and arrangement of parts may be resorted to without departing from the spirit 65 of the invention or the scope of the subjoined claim.

Having thus described the invention, we claim:—

A display rack comprising a base, a pair of angle iron side frames mounted on said base in spaced parallelism, transverse brace members connecting the side frames intermediate the upper and lower extremities of the same, a pair of closely positioned, parallel brace members connecting the upper extremities of the side frames and being formed of pipe sections having tie bolts extending through their bores and through apertures formed in flanges of the angle iron side frames, horizontal strip members fastened to each side frame by relatively long tie bolts which project laterally of the frames and have their free portions encircled by pipe sections for forming pegs, lateral pegs mounted on said transverse brace members and horizontal strip members and including pipe sections supported by tie bolts extending through their bores and through apertures in said members, and a plurality of double pegs mounted on said side frames, said double pegs each including 70 a pair of axially aligned pipe sections arranged one on each side of a frame member and secured thereto by a bolt passing through the bores of said pipe sections and an aperture in a flange of said side frame. 75

In testimony whereof we affix our signatures.

WILLIAM C. LYON.
ALPHEUS McCULLEN.
